UNITED STATES PATENT OFFICE.

JOSEPH C. EARNSHAW, OF YONKERS, NEW YORK.

DESIGN FOR A CURTAIN.

SPECIFICATION forming part of Design No. 22,120, dated January 10, 1893.

Application filed December 10, 1892. Serial No. 454,786. Term of patent 7 years.

To all whom it may concern:

Be it known that I, JOSEPH C. EARNSHAW, a citizen of the United States, residing at the city of Yonkers, in the county of Westchester and State of New York, have invented and produced a new and original Design for Curtains and Similar Fabrics, of which the following is a specification, reference being had to the accompanying drawing, forming a portion 10 of the specification, which illustrates a face view of portion of a curtain embodying my design.

The invention relates to a design to be worked into fabric, and consists in the novel 15 configuration and grouping of the figures herein specifically shown and claimed.

The design consists of a body, A, and a border, B. The body, A, consists of floral figures and scroll work at the upper portion of which 20 is a representation of part of a winged dragon.

The border, B, consists of a lateral section representing a series of scroll bordered entablatures, b, having intermediate downwardly depending floral leaf work, c. From this section of the border and springing upwardly therefrom is a combination of scrolls and leaves which support the upper portion of a human figure with hands uplifted supporting a basket of flowers, from which spring leaves and terminating in curves upon which are two human 25 figures seated on a rosette.

I claim;—

The design for curtains consisting of the body, A, and border, B, substantially as shown and described.

JOS. C. EARNSHAW.
